UNITED STATES PATENT OFFICE.

WILLIAM RABICH, OF ST. LOUIS, MISSOURI, ASSIGNOR TO THE ARTISTIC ENAMELING WORKS, OF SAME PLACE.

RANGE.

SPECIFICATION forming part of Letters Patent No. 651,384, dated June 12, 1900.

Application filed December 22, 1898. Serial No. 700,048. (No model.)

To all whom it may concern:

Be it known that I, WILLIAM RABICH, a citizen of the United States, residing at St. Louis, in the State of Missouri, have invented 5 certain new and useful Improvements in Ranges; and I do hereby declare the following to be a full, clear, and exact description of the invention, such as will enable others skilled in the art to which it appertains to 10 make and use the same.

My invention relates to improvements in ranges; and it consists in the novel combination and arrangement of parts, as will be hereinafter more particularly described and 15 claimed.

In the drawings, Figure 1 is a front elevation of my complete invention. Fig. 2 is a perspective view of one of the doors. Fig. 3 is a detail cross-section through a portion 20 of one of the frames for the doors. Fig. 4 is an edge view of one of the doors. Fig. 5 is a perspective view of one of the pins which form the hinge for the door. Fig. 6 is a detail cross-section of a portion of the door and 25 frame for same about its hinged portion. Fig. 7 is a vertical section of the range, taken through the over and draft flues of the same. Fig. 8 is a combined side elevation and vertical section of the frame and door of the 30 coal-box. Fig. 9 is a combined side elevation and vertical section of one of the lower doors and frame for same. Fig. 10 is a detail sectional view of the frame and bearing 35 for the doors. Fig. 11 is a horizontal cross-section taken on the line $\alpha\alpha$ of Fig. 1, showing one corner of the range and the manner in which the several parts are connected; and Fig. 12 is a vertical section of the fire shield or plate which is carried and operated by the 40 door for the fire-box.

The object of my invention is to construct the doors of a range in such a manner that the outer surfaces thereof may be perfectly smooth in order that they may be practically 45 enameled in any shade or color, whereby the range will not only present a neat and attractive appearance, but can be easily

cleaned, thus dispensing with the laborious work which has been necessary to keep other ranges in a clean and attractive condition. 50

The parts comprising the doors are so constructed as to be attached from the inside without the outside presence of screws or other fastening devices.

Referring to the drawings, 1 represents a 55 range the draft-flues of which are of the usual construction, and 2 a hinge-damper, to which is attached a rod 4, leading to one end of the range and operated by a sliding knob 5, located at that end of said range and in easy 60 reach of the operator.

The sheet metal 6, which comprises a greater portion of the range, is preferably enameled on its outer surface, and the metallic frames 7, which form the trimmings, 65 are preferably nickel-plated, which gives the range a very neat and attractive appearance. The said frames 7, which surround the various openings in the front of the range and which are adapted to be covered by the various doors, (which are of sheet metal and likewise enameled,) are similarly constructed and are fastened or removably secured to the front of the range and in their proper position in respect to the openings formed there- 70 in by screws 8, which are inserted from the inside of the range and are passed through openings formed for their reception in the sheet-metal portions of the same and are screwed into said trimmings. In order to 80 secure the corners of the range together, bars 9 are employed, which preferably run the full height of the range proper, and the metal which forms the body portion of said range is bent at an angle at a suitable distance 85 from the edges thereof and are adapted to be overlapped at their bent portions, through which portions screws 10 are passed through suitable openings formed for their reception and are screwed into the bars 9, thereby 90 forming a movable connection for those portions of the range, as clearly shown in Fig. 11.

The various sheet-metal doors which comprise the range are likewise similarly con-

structed and are hinged to the opposite sides of the frames 7, adjacent to the lower portions thereof, in a manner now to be described.

In forming the sheet-metal doors 7' tongues 5 or extensions 11 are left, which are located at the opposite lower edges of the same and form a continuation of the lower edges of the plates which form the doors, and adjacent to said tongues the metal is sufficiently depressed 10 outwardly, after which the said tongues are bent upwardly and toward the depressed portions 12, flush with the inner surface of said door, forming sockets 13, having each a rounded and flat inner surface, which sockets 15 are adapted to snugly but removably receive the reduced or similarly-shaped ends 14 of the pins 15, with their rounded ends projecting from the opposite edges of the doors, whereby the said pins may be removed from 20 the doors before the latter are subjected to the process of enameling. Located at the lower opposite corners of the frames 6 are sockets 16, which are adapted to receive the rounded projecting ends of the pins 15, whereby 25 the doors are properly united to the range.

Removably located within the fire-box and arranged in the inside thereof and in contact with the inner surface of the metallic wall 6 of one of the sides of the range is a frame 17, 30 the lower portion of which is provided with a rod 18, over which the hook extension 19, forming an integral part of the metallic fire guard or plate 20, is removably hooked, thereby forming a hinged connection between said 35 guard and frame.

The fire-guard and its door 7' are movably connected to one another by side plates 21, which are attached to said door and project inwardly therefrom and are each provided 40 with inclined slots 22, which receive the pins 23, projecting from the opposite sides of the fire-guard 20. By this arrangement the fire-guard 20 not only protects its door 7', but on account of its hinged connection, or, in other 45 words, its weight being in the rear of its hinged connection, the door 7' is held in a closed position. Furthermore, it is to be noticed in this connection that when the door 7' is in a closed position there is a sufficient 50 amount of space between the fire-guard and door for the circulation of air, which will operate to keep said door comparatively cool. When the door 7' is open, the fire-guard 20 is carried by the same, the lugs 24, forming a 55 part of the same, being adapted to rest upon the lower edge of the frame 7, whereby the weight of said guard is relieved from the door when the latter is in an open position, as clearly shown in the dotted lines in Fig. 8. 60 The range as constructed is provided with the usual soot-opening 25 and door for same and also an opening and door 26 for the ash-pan. Located above the opening and door covering for the ash-pan is an opening 65 rounded by a frame 27, having a hinged door 28, which can be regulated to give the re-

quired draft to the fire below the same. The door 28, covering the draft-opening, and door 26, covering the ash-pit, are each provided with a segmental plate 29, which is secured 70 to and carried by the same and is provided with an extension 30, the inner edge of which is adapted to come in contact with the inner wall of the body of the range for limiting the movement of the doors when in an open position. The segmental plates 29 also operate to hold the doors in any adjusted position, the sides of which are in yielding frictional contact with the sides of the openings through which they pass, or, more properly, the vertical walls of the same. 75 80

Having fully described my invention, what I claim is—

1. In a range, a sheet-metal door, tongues forming a continuation of the same, depressions formed in said door adjacent to the tongues, the latter being bent back over said depressions flush with the inner face of said door, forming sockets, and pins adapted to be received by the sockets thus formed with 90 one of their ends projecting a suitable distance from the opposite edges of the door, as and for the purpose described. 85

2. In a range, a sheet-metal door, tongues forming a continuation of the same, depressions formed in said doors adjacent to the tongues, the latter being bent back over said depressions, flush with the inner surface of said door forming sockets having rounded and flat inner surfaces, and pins, one end of which corresponds in shape to the said sockets, and having their opposite ends projecting a suitable distance from the opposite edges of the door, as and for the purpose described. 95 100

3. In a range, a fire-box opening, a sheet-metal door, the lower edge of which is hinged to the range, and adapted to cover said opening, a frame removably located within the fire-box, adjacent to the opening formed therein, a fire-shield, the lower edge of which is hinged 110 to the said frame, slots formed in the opposite sides of the hinged doors, and pins projecting from the opposite sides of the fire-shield, and adapted to be received by the slots carried by the door, as and for the purpose 115 described. 105

4. In a range, a fire-box opening, a sheet-metal door, the lower portion of which is hinged to the range, and adapted to cover said opening, a frame removably located within the fire-box, adjacent to the opening formed therein, a fire-shield, a hooked extension projecting from the lower edge of the same, means carried by said frame with which the hooked extension co-operates, slots formed in the opposite sides of the hinged door, and pins projecting from the opposite sides of the fire-shield, and adapted to be received by said slots, whereby a space is formed between the door and shield when the former is in a closed 130 position, substantially as described. 120 125

5. In combination with a hinged door, side

plates attached to the inner surface of the same, and projecting therefrom, inclined slots formed in the same, a frame adapted to be located within the fire-box, adjacent to the opening formed therein, a fire-shield, a hooked extension projecting from the lower edge of the same, a rod carried by said frame, with which the hooked extension co-operates, and pins projecting from the opposite sides of said

fire-shield, and adapted to be received by the slots formed in the side plates, carried by the door, as and for the purpose described.

In testimony whereof I affix my signature in presence of two witnesses.

WILLIAM RABICH.
